UNITED STATES PATENT OFFICE.

OSCAR FREYMAN AND CHARLES TOLMAN, OF BROOKLYN, NEW YORK,
ASSIGNORS TO AMERICAN EQUIPMENT COMPANY, OF NEW YORK, N. Y.,
A CORPORATION OF NEW YORK.

GAS-DETECTOR.

SPECIFICATION forming part of Letters Patent No. 692,007, dated January 28, 1902.
Application filed April 15, 1901. Serial No. 55,897. (No model.)

To all whom it may concern:

Be it known that we, OSCAR FREYMAN and CHARLES TOLMAN, of the borough of Brooklyn, county of Kings, city and State of New York, have invented certain new and useful Improvements in Gas-Detectors, of which the following is a full, clear, and exact specification, reference being had to the accompanying drawings, wherein—

10 Figure 1 is an elevation partly-sectional view of an apparatus gas-detector, showing one form of performing and using our invention. Fig. 2 is a similar view of the same apparatus, taken at right angles to Fig. 1. Fig. 15 3 is a plan view thereof.

Our invention relates to automatic alarm devices; and it consists of the hereinafter-described apparatus for detecting and signaling the presence of gas escaping in the place 20 where the apparatus is located.

The apparatus shown and described herein is designed to be used in connection with an electrically-operated signaling device, its 25 function in this combination being to effect the closing of the electric circuit; but the apparatus may also be used in connection with a mechanically-operated signaling device.

The operating parts of the apparatus shown in the drawings are arranged in and secured 30 to a frame consisting of bracket 1 and plate 2, joined to insulating-plate 7 by screws 8 and 9, respectively, plate 3, bolts 4, joining plates 2 and 3 together, and brackets 5, whereby the frame is secured by screws 10 to the metallic casing 6, inclosing the apparatus. Casing 6 is provided with aperture 37 and perforations 38 in the bottom part thereof and with apertures 40 farther above to permit gas to freely pass through the apparatus. The 35 40 casing is made integral with or affixed to a socket 42, whereby the apparatus can be affixed to the wall or ceiling of a room.

The operating mechanism of the apparatus is arranged as follows: The stationary contact-piece 29, connected by wire 31 to a battery or other generator of electric current, is set on top of bracket 1 and secured thereto by screw 30, and the movable contact-piece 27 is mounted upon the oscillating lever 25, which is pivoted

on pin 26, set in plates 2 and 3. This movable contact-piece 27 is connected to the same battery or electric-current generator through lever 25, pin 26, plates 2 and 3, brackets 5, casing 6, and wire 28. In the same electric current is included an electric bell or other signaling device, and also an annunciator, indicating the location of the apparatus by number or otherwise, may be included therein. Lever 25 is provided with a recess 24, wherein the longer arm of lever 19, oscillating on pin 20, engages. Spring 32, secured on a pin set in plate 2, acts upon the shorter arm of lever 19, pressing it upwardly, and thereby its longer arm engaging in recess 24 of lever 25, as hereinbefore explained, 65 draws the movable contact-piece 27 downwardly, pressing it in contact with the stationary contact-piece 29, whereby the electric circuit from the battery and through the signaling device and through the apparatus and back to the battery is closed.

The signaling device and the annunciator are set in action when the electric circuit is closed, and therefore the apparatus must normally be held in "inactive position"—to wit, 75 with the contact-pieces separated from each other by a device whose capacity for holding the contact-pieces apart will be destroyed by the action of gas when entering the apparatus.

In the construction of our apparatus we 80 utilize the substance known as "platinum sponge," which, as it is well known, becomes rapidly heated when exposed to the action of illuminating-gas. For the purposes of our apparatus it is best to prepare a bath of 85 six parts of platinum chlorid and of twelve parts of aluminium chlorid, wherein a porous substance—such as, for instance, rare clay, sepiolite, or the like—suitably shaped is immersed for a period of from two to three hours, 90 then dried, and afterward washed in a bath of hydrochloric or of sulfuric acid. This washing must be repeated until all impurities are removed, and then all traces of the acids washed out in a bath of water and finally in a bath of ether. In place of rare clays or sepiolite coke may also be used; but rare clays are best suited for the purpose. 95

The porous substance is preferably made up in bars or plates, and such bars or plates prepared as hereinbefore described are then placed in close proximity to the device, where-
5 by the contact-pieces are held separated and which must be such that heat acting upon it will cause it to relax or release its hold upon the contact-pieces or the mechanism pressing them one upon the other. When illuminat-
10 ing-gas enters the apparatus, it causes these bars or plates to glow, the heat emanating therefrom produces the desired effect upon the device holding the contact-pieces sepa-
15 rated, and the apparatus is thereby set in action.

In the construction shown in the drawings the device for holding the contact-pieces normally separated and for releasing them by the action of gas is arranged as follows:
20 The downwardly-pointing arm of bracket 1 is extended and formed into a shank 11, and a grooved roll 13 is mounted to loosely re-
volve on pin 14, set in tines 12 of its bifur-
cated end. On the end of the horizontal arm
25 of bracket 1 a sleeve 15 is secured, wherein
the shank of hook 16 is inserted and held by
nut 17. The shank of hook 16 is bent to one
side, as shown in Fig. 2, to bring the hook
proper (designated 18 in the drawings) in line
30 with the groove of roll 13. To this hook the
connecting device 21, either combustible or
expansible by heat—as, for instance, a com-
bustible thread or a metallic wire (preferably
thin platinum wire)—is secured. This con-
35 necting device is drawn over roll 13, and its
other end is secured to the short arm of lever
19 directly or through the medium of an in-
termediate hook 22, as shown in Fig. 1 of the
drawings. The connecting device is stretched
40 by screwing nut 17 on the end of shank 16,
while the short end of lever 19 is pressed
downward against the action of spring 32 to
separate the movable from the stationary con-
tact-piece. The bars, strips, or plates 33 of the
45 porous substance treated as described above
are supported on brackets 34, affixed to shank
11, and are held in such position as to be al-
most in contact with the connecting device 21.
When gas enters the apparatus, the connect-
50 ing device 21, holding the contact-pieces sepa-
rated, is heated, and if a metallic wire is used
for that purpose is elongated. Lever 19 is
thus released and yields to the action of spring
32 and the contact-pieces are brought to-
55 gether, the circuit closed, and the signaling
apparatus set in action.

In place of a metallic wire a combustible
thread may be used as the connecting device
21, with the same ultimate effect, except that
60 instead of being elongated the combustible
thread is destroyed by the glowing heat, and
therefore must after every action of the ap-
paratus be replaced, whereas if metallic wire
is used the wire need not be replaced after
65 every action of the apparatus, but merely re-
adjusted, which is done by screwing nut 17
in the manner explained above.

The sensitiveness of the apparatus is ad-
justed by setting the movable contact-piece
70 27 farther away from or nearer to the sta-
tionary contact-piece 29. The greater the
distance between the two the longer it will
take to set the apparatus in action, and the
nearer the contact-piece 27 is set to contact-
piece 29 the sooner the alarm will be sounded. 75

Our improved apparatus for detecting gas
escaping in a room may also be made so as
to serve at the same time for detecting smoke
in the manner described in our application
for Letters Patent, filed April 1, 1901, Serial
80 No. 53,803. For this purpose we use a thread
of silk, a horsehair, or other similarly-com-
posed fiber, which before using it we boil (in
a closed vessel) in a six to ten per cent. solu-
85 tion of commercial soda for about twenty
minutes and then dry it very moderately
stretched in a tube from which the air is ex-
hausted. The diameter of the fiber should
not be less than that of the coarse horsehair.
It is better to twist or braid two or three of
90 such fibers into a string or cord, the capacity
of such string or cord to be contracted by the
treatment and elongated again when exposed
to smoke being greater.

The solution of soda must not be stronger
than ten per cent., and nothing but pure com-
mercial soda must be used in preparing it.
A strong solution might impair the tensile
strength of the fiber, which of course must
be sufficient for the purpose of this appara-
tus, or might even dissolve it.

The thread, hair, or string is contracted by
the treatment, but retains its tensile strength
and acquires the quality to elongate when
exposed to smoke. 105

We are unable to precisely explain what
transformation is produced in the fiber by
treating it as hereinbefore explained or what
particular component of smoke produces its
elongation. We believe that the vapors of
110 volatile oils produced by combustion or some
of the gases contained in the smoke produce
the change in the composition of the fiber.
We made numerous tests with fibers treated
as above described and found that smoke in-
115 variably produced the elongation of the fiber
thus treated, though some smoke—as, for in-
stance, smoke produced by burning wood—
acts more rapidly than others.

Our gas-detecting apparatus thus ampli-
fied by the employment of such smoke-sensi-
tive thread or fiber for the connecting device
21 signals the presence of smoke as well as
of gas in the room or compartment wherein
such apparatus is located, the smoke pro-
ducing the closing of the electric circuit by
elongating the sensitive thread, whereas when
gas passes through the apparatus the sensi-
tized fiber is disintegrated by the heat ema-
nating from the glowing bars or plates 33. 125
In both cases lever 19 is released and spring
32 presses the contact-pieces together, where-
by the electric circuit is closed and the sig-
naling or announcing device set in action. 130

We are aware that the principle of our invention may be embodied in still other forms of mechanical arrangement of the parts of such apparatus, and more particularly the 5 combination of our gas-detecting apparatus with the smoke-detecting apparatus described in our aforementioned application for patent may be accomplished in various other ways besides those we have shown; but we consider 10 the apparatus illustrated in the drawings as the best form of the embodiment of our invention and the use of the sensitized fiber as the connecting device 21 as the best form of combination whereby one apparatus 15 can be made to serve for both purposes simultaneously.

We claim as our invention—

1. The combination with an automatic circuit-closing device of a connecting device, 20 sensitive to the action of heat, for holding the contact-pieces apart, and of a piece or pieces of porous substance, affixed in proximity to the connecting device; said porous substance being treated with chemical composition as 25 herein described and thereby rendered productive of heat when exposed to the action of gas.

2. The combination with the movable contact-piece of an automatic circuit-closing device of a connecting device, sensitive to the 30 action of heat; said connecting device being attached to the movable contact-piece and holding it away from the other contact-piece, and of a piece or pieces of porous substance, affixed in proximity to the connecting device; said porous substance being treated with chemical composition as herein described and thereby rendered productive of heat when exposed to the action of gas.

3. The combination with an automatic circuit-closing device, comprising a stationary and a movable contact-piece, of a connecting device, sensitive to the action of heat, attached to the movable contact-piece and holding 45 it away from the other, and of a piece or pieces of porous substance, affixed in proximity to the connecting device; said porous substance being treated with chemical composition as herein described and thereby rendered productive of heat when exposed to the action of gas.

4. The combination with mechanism, actuating a signaling device and a spring-actuated lever for starting or releasing the mechanism, of a connecting device, sensitive to the 55 action of heat, attached to the lever and holding it against the action of the spring, and of a piece or pieces of porous substance, affixed in proximity to the connecting device; said porous substance being treated with chemical composition as herein described and thereby rendered productive of heat when exposed to the action of gas.

5. A gas-detecting device comprising an 60 electric battery, an electrical signaling device, a frame, a stationary and a movable contact-piece, mounted in the frame, electrical

conduits connecting the battery, the signaling device and the contact-pieces, mechanism acting upon the movable contact-piece, a connecting device, sensitive to the action of heat, attached to the movable contact-piece and holding it away from the stationary contact-piece, and a piece or pieces of porous substance, affixed in proximity to the connecting device; said porous substance being treated with chemical composition as herein described and thereby rendered productive of heat when exposed to the action of gas.

6. A gas-detecting device comprising an 80 electric battery, an electrical signaling device, a frame, a stationary and a movable contact-piece, mounted in the frame, electrical conduits connecting the battery, the signaling device and the contact-pieces, mechanism 85 acting upon the movable contact-piece, a connecting device, sensitive to the action of heat, connected to the movable contact-piece and holding it away from the stationary contact-piece, and a piece or pieces of porous substance, affixed in proximity to the connecting device; said porous substance being treated with chemical composition as herein described and thereby rendered productive of heat when exposed to the action of gas.

7. The combination with an automatic circuit-closing device of a combustible connecting device for holding the contact-pieces apart, and of a piece or pieces of porous substance, affixed in proximity to the connecting 100 device; said porous substance being treated with chemical composition as herein described and thereby rendered productive of heat when exposed to the action of gas.

8. The combination with mechanism actuating a signaling device and a spring-actuated lever for starting or releasing the mechanism, of a combustible connecting device attached to the lever and holding it against the action of the spring, and of a piece or pieces of porous substance, affixed in proximity to the connecting device; said porous substance being treated with chemical composition as herein described and thereby rendered productive of heat when exposed to the action of gas.

9. A gas-detecting device, comprising an electric battery, an electrical signaling device, a frame, a stationary and a movable contact-piece, mounted in the frame, electrical conduits connecting the battery, the signaling device and the contact-pieces, mechanism acting upon the movable contact-piece, a combustible connecting device attached to the movable contact-piece and holding it away from the stationary contact-piece, and a piece 120 or pieces of porous substance, affixed in proximity to the connecting device; said porous substance being treated with chemical composition as herein described and thereby rendered productive of heat when exposed to the 125 action of gas.

10. The combination with an automatic circuit-closing device of a combustible connecting device for holding the contact-pieces apart,

- said connecting device being treated as herein described, whereby it is rendered sensitive to the action of smoke, the smoke causing it to elongate, and of a piece or pieces of a porous substance, affixed in proximity to the connecting device; said porous substance being treated with chemical composition as herein described and thereby rendered productive of heat when exposed to the action of gas.
11. A combined smoke and gas detecting device comprising an electric battery, an electric signaling device, a frame, a stationary and a movable contact-piece, mounted in the frame, electric conduits connecting the battery, the signaling device and the contact-pieces, mechanism acting upon the movable contact-piece and forcing it in contact with the stationary contact-piece; a combustible con-

necting device connected to the movable contact-piece, and holding it away from the stationary contact-piece; said connecting device being treated as herein described, whereby it is rendered sensitive to the action of smoke, the smoke causing it to elongate; and a piece or pieces of a porous substance, affixed in proximity to the connecting device; said porous substance being treated with chemical composition as herein described and thereby rendered productive of heat when exposed to the action of gas.
